(57) **CLAIM**

The ornamental design for a tray, as shown and described.

DESCRIPTION

FIG. 1 is a perspective view of a tray;

FIG. 2 is a top view thereof;

FIG. 3 is a bottom view thereof;

FIG. 4 is a right end view thereof;

FIG. 5 is a left end view thereof;

FIG. 6 is a rear view thereof; and,

FIG. 7 is a front view thereof.

In the drawings, the evenly-spaced broken lines showing printed outlines and a hole for intubation equipment depict environmental subject matter that forms no part of the claimed design.
